DISPENSING CONTAINER

Marshall I. Williamson, New Haven, Conn., assignor, by mesne assignments, to National Folding Box Company, Incorporated, a corporation of Connecticut

Application July 29, 1943, Serial No. 496,538

7 Claims. (Cl. 229—17)

1

This invention relates to dispensing containers, and more particularly to containers which are adapted to be formed of paperboard or other suitable and readily available material for the packaging of powdered or granular substances and pills, pellets, or tablet-like articles such as are normally dispensed by the consumer from the container as needed.

In accordance with this invention a container is provided which is formed from a single blank of paperboard or other suitable material, which presents enclosing side and end walls. One of the enclosing side walls comprises an inner panel and an overlying outer panel. In the outer of these two panels an opening is provided and, directly beneath this opening, an area of the inner panel is adapted to be pierced, pressed in or removed by the consumer so as to form an opening or a group of openings in registry with the opening in the outer panel through which the contents of the container may be dispensed.

In the outer panel only, there is also provided, somewhat remote from the dispensing opening, an arcuate or substantially U-shaped slit, arranged transversely of the panel.

In forming the container, pursuant to this invention, prior to the filling with its intended contents, a flat, card-like closure member of suitable material, size and configuration, is inserted between the aforesaid overlying wall panels and positioned and arranged for snug, sliding movement therebetween.

A tab of suitable length extends from an edge of this closure member and projects through the aforesaid arcuate or U-shaped slit in the outer of the two overlying wall panels, so that it may readily be grasped from the outside and afford convenient finger operable means for sliding the member back and forth to alternately clear and close the registering dispensing openings in the said overlying wall panels of the container.

In certain forms of the invention, the container may be so constructed as to prevent sifting loss of its powdered or granular contents. These siftproof forms of the container are provided with a pair of inner inturning flaps extending from each end side of the inner of the said overlying wall panels, and a pair of outer inturning flaps extending from each corresponding end of the outer of said panels. The outer flaps are somewhat shorter than the inner flaps and overlie the latter when the container is sealed. This permits the end sealing flaps, which ultimately overlie the respectively adjacent inner and outer inturning flaps, to be adhesively secured to both

2

of these flaps, thereby preventing sifting of the contents therebetween and thus blocking further sifting of the contents between the said inner and outer overlying wall panels of the container and consequent possible loss of the contents therefrom.

According to a preferred form of this invention, a folding box or carton is provided having three side walls of single thickness, a side wall of double thickness and end walls of multiple thickness, the double thickness side wall having an opening therein and a closure for said opening. The carton itself is formed from a single prepared flat blank of foldable sheet material such as paper boxboard and, except for the multi-thick end walls and the double-thick side wall, is of conventional end-sealable folding box style.

To provide the stated double-thick top wall of the carton, an inner or primary side wall forming panel is integrally and hingedly connected to the top edge of one side wall of the carton and an outer or secondary side wall forming panel is similarly connected to the top edge of the opposite side wall of the carton. At the ends of each 25 of these two side wall forming panels which is opposite their respective thus-connected edges, there is similarly connected a relatively short securing flap. In first forming the carton from its flat blank into a collapsed tubular shell, as is normally required, the securing flap of the inner side wall panel is adhesively secured to the inside and adjacent the top edge of one side wall 30 of the carton and, thereafter, the securing flap of the outer side wall panel is adhesively secured to the outside and adjacent the top edge of the wall opposite said one side wall. By this arrangement the outer or secondary side wall panel securely and closely overlies the inner or primary side wall panel without itself being adhesively 35 secured thereto.

To provide the multi-thick end walls of the carton, an end wall supporting flap is integrally and hingedly connected to each end edge of the side wall of the carton opposite the double side 45 wall and an identical such flap is similarly connected to each end edge of the inner side wall panel of the carton. These flaps preferably are of such length that, when those associated with the side wall opposite the double side wall are 50 turned inwardly toward those associated with the double side wall panel of the carton, their respective ends will meet and lie in substantially edge-to-edge abutting relationship. Similarly connected to each end of the outer side wall panel 55 of the carton is another such flap substantially

shorter but otherwise identical with and adapted, when similarly inturned, to overlie the flaps connected to the inner side wall panel. Also similarly connected to the ends of one of the remaining single thickness side walls of the carton is a sealing panel which, is adapted to overlie and be adhesively secured to the previously inturned end wall supporting flaps. Likewise connected to the ends edge of the remaining end wall of the carton is a substantially identical end wall sealing panel which, is adapted to fully overlie and be adhesively secured to the previously inturned end wall sealing panel, thus completing the formation of the stated multi-thick end walls of the carton.

Both the inner and the outer side wall pane's of the carton have formed therein, or are adapted to have formed therein, an aperture which may be of considerable size and extend from near the same lateral side of each such panel to about the center thereof, the two apertures when formed being in substantial alignment or register so as to provide an opening in the side wall of the carton for access to or dispensing of the contents. Prior to sealing the multi-thick end walls this access or dispensing opening is provided with a closure in the form of a substantially T-shaped card-like member which is slidably arranged between the said inner and outer side wall panels of the carton and is adapted for easy exterior manipulation by means of a tab portion which projects through a substantially U-shaped slit in the outer of the said side wall panels. This U-shaped slit has its legs directed toward and preferably terminating at that fold defined lateral edge of said outer end wall panel which is the more remote from the said aperture therein.

The T-shaped closure member comprises a rectangular main or body portion of a width substantially equal to the width of the carton side panel and a length substantially equal to one-half the length of the carton end panel, and a narrower rectangular stem or tab portion integral with the body portion and adapted to enter and extend outwardly through the said U-shaped slit in the outer side wall panel of the carton when the closure member is inserted between the inner and outer side wall panels thereof, the width of the said tab portion being substantially equal to that of the U-shaped slit and its length being substantially equal to that of the body portion of the closure member. In its sliding movement, the closure member is guided and frictionally restrained by the close fit and confinement of its body portion between the inner and outer side wall panels of the carton, the parallel side edges of the body portion riding along the hinge-fold-connected front and back edges respectively of the said panels and the side edges of the tab portion riding along the parallel legs of the U-shaped slit, thus assuring a smooth and straight but frictionally retarded sliding movement of the said closure member. The forward shoulder edges of the closure member, at either side of the tab portion, form abutment means for cooperation with the ends of the U-shaped slit, and preferably also with the adjacent fold-defined lateral edge of the outer side wall panel of the carton, to limit the sliding movement of the closure member in that direction and prevent its complete withdrawal therefrom. The sliding movement of the closure member in the opposite direction is similarly limited by abutment of its rearward edge against the opposite fold-defined lateral edge of the outer side wall panel of the carton. The overall length of the closure mem-

ber preferably does not exceed the length of the inner side wall panel of the carton between its respective fold-defined lateral edges so that the closure member will lie entirely within the area thereof when in aperture closing position.

The box or carton so constructed is free from projections extending beyond its walls and thus, when collapsed, permits convenient packing and stacking without waste of space. The manually operable tab portion of the closure member is easily accessible by reason of the improved form of the slit in the shape of a U exposing a substantial length of the tab portion for gripping equal to the height of the U measured from the bottom of the U to the ends of its legs. The height of the U does not limit the length of the longitudinal movement of the closure member in any way since the member may be moved until its abutment edges reach the ends of the legs of the U-slit which preferably terminate at one edge of the outer top wall panel. In other words, the use of a U-shaped slit with a T-shaped closure member offers the advantage of a well accessible and exposed finger operable portion of the closure member without a limitation of the length of its longitudinal movement, thus permitting the use of an unusually large dispensing aperture.

The features of this invention may be incorporated in containers of various shapes and forms by proper design and shaping of the container forming blank. The container forming blank is so cut and scored and its respective panels and flaps are so arranged as to permit high speed gluing and folding assembly thereof into collapsed shell form on a standard strip gluing and folding machine. The blanks are further so shaped and formed that the collapsed shell assembled therefrom may be erected into container form and the opposite open ends or sides thereof closed and sealed on a standard end sealing machine, or by a simple hand operation. No special machinery therefore need be employed in the preparation of the blanks, or the assembly of the blanks in collapsed shell form, or the erection, closing and sealing of the shells. Cartons or containers made in accordance with this invention are therefore adapted for manufacture and assembly by high speed and yet standard container assembly machines at low cost without skilled labor to provide a packaging medium which is highly useful and serviceable in the packaging and merchandising of products of various types which have heretofore been packaged mainly in cans or boxes partially or wholly formed of sheet metal.

These and other features, objects and advantages of the invention will appear more fully from the detailed description which follows accompanied by drawings showing, for the purpose of illustration, a preferred embodiment of the invention.

The invention also consists in certain new and original features of construction and combination of parts hereinafter set forth and claimed.

Although the characteristic features of the invention which are believed to be novel will be particularly pointed out in the claims appended hereto, the invention itself, its objects and advantages, and the manner in which it may be carried out, may be better understood by referring to the following description taken in connection with the accompanying drawings forming a part thereof in which:

Fig. 1 is a plan view of the inside face of a prepared blank from which my improved dispensing container may be formed;

Fig. 2 is a plan view of a prepared blank for the closure member;

Fig. 3 is a perspective view of the prepared container blank as it appears after having passed through the first glue wheel and folding operations;

Fig. 4 is a perspective view of the prepared container blank as it appears after having passed through the second folding operation and as it is about to pass through the second glue wheel operation;

Fig. 5 is a perspective view of the prepared container blank as it appears after having passed through the second glue wheel and the third folding operations to provide a collapsed glued tubular shell;

Fig. 6 is a perspective view of the collapsed shell after expansion thereof into rectangular tubular form, showing the end wall supporting flaps on one end of the container in the process of being brought into closed position;

Fig. 7 is a perspective view of the partially assembled container showing one pair of side wall sealing panels folded outwardly in the position in which adhesive has been applied to their inner surfaces;

Fig. 8 is a perspective view of the partially assembled container showing the same pair of end wall sealing panels as they appear when brought to substantially closed position;

Fig. 9 is a perspective view showing the partially assembled container inverted from its previous position with one end fully closed and the closure member in the process of insertion, the container being ready to be filled with merchandise;

Fig. 10 is a perspective view of the partially assembled container, filled with merchandise, showing the closure member fully inserted and the merchandise receiving side in the first stage of being closed and sealed;

Fig. 11 is a perspective view of the container showing the last pair of end wall sealing panels in outspread position after having adhesive applied thereto;

Fig. 12 is a perspective view of the filled container as it appears during the final sealing stage;

Fig. 13 is a perspective view of the fully assembled, filled and sealed container showing the closure member drawn to dispensing position and the removable portion still in place;

Fig. 14 is a vertical cross-sectional view through the fully assembled, filled and sealed dispensing container as it appears when viewed along line 14—14 of Fig. 13, when the closure member is in operative closing position;

Fig. 15 is a vertical cross-sectional view through the fully assembled, filled and sealed dispensing container as it appears when viewed along line 15—15 of Fig. 13, with the closure member in operative closing position;

Fig. 16 is a vertical cross-sectional view through the upper portion of the container and similar to the view shown in Fig. 14 except that the closure member has been drawn into dispensing position with the dispensing opening in the container fully exposed and the removable portion removed;

Fig. 17 is a plan view of the inside face of a prepared blank from which a dispensing container of somewhat modified construction may be formed;

Fig. 18 is a plan view of a blank of a closure member for the container assembled from the blank shown in Fig. 17;

Fig. 19 is a perspective view of the container as-

6

sembled from the blank shown in Fig. 17 with all sides closed save one end, this view also showing the closure member in process of being inserted;

Fig. 20 is a perspective view of the fully assembled and filled container formed from the blank shown in Fig. 17, this view showing the closure member drawn to dispensing position;

Fig. 21 is a plan view of the inside face of a prepared blank from which a dispensing container of further modified construction may be formed;

Fig. 22 is a plan view of a blank of a closure member for the container assembled from the blank shown in Fig. 21;

Fig. 23 is a perspective view of the blank shown in Fig. 21 as it appears after having passed through the first glue wheel and folding operations;

Fig. 24 is a perspective view of the blank shown in Fig. 23 as it appears after having passed through the second folding operation and is about to pass through the second glue wheel operation;

Fig. 25 is a perspective view of the blank shown in Fig. 24 after having passed through the second glue wheel and the third folding operations to provide a collapsed glued tubular shell;

Fig. 26 is a perspective view of the tubular shell after expansion or erection into rectangular form, this view showing the flaps forming one end wall of the container in the process of being closed;

Fig. 27 is a perspective view of the partially assembled container showing one end wall fully closed;

Fig. 28 is a perspective view of the partially assembled container as shown in Fig. 27 in inverted position, one end wall being closed and one end wall open and arranged in position to receive the contents, this view also showing the closure member in the process of being inserted;

Fig. 29 is a perspective view of the fully assembled modified container formed from the blank shown in Fig. 21 with the closure member drawn into dispensing position; and

Fig. 30 is a longitudinal cross-sectional view through the fully assembled container as it appears when viewed along line 30—30 of Fig. 29.

Similar reference characters refer to similar parts throughout the several views of the drawings and the specification.

The blank A as shown in Fig. 1 is especially designed to form a dispensing container for powdered or granular products which normally have a tendency to sift through openings and spaces which are not fully and completely sealed. The

blank A is especially designed to overcome such leakage difficulties and provide a container which can be economically manufactured and assembled on standard box assembling machines at a high production rate. It will be noted that the

blank shown in Fig. 1 is substantially rectangular in outline, resulting in a minimum waste of material. The blank may be cut and scored in multiple from a large sheet or roll of paperboard or other suitable material on an automatic cutting and scoring machine. Only one side of the

blank need be finished or imprinted since only one surface of the blank is presented as the outside face of the assembled container.

The blank A comprises a panel 1, which for convenience in description may be called a side wall panel. A panel 2, which for convenience in description may be referred to as a rear wall panel, is hinged to the bottom wall panel 1 along the score line 4. An opposite panel 3, which for convenience in description may be referred

to as a front wall panel, is hinged to the opposite edge of the side wall panel 1 along a score line 5 extending substantially parallel to the score line 4. An inner panel 6, which may for convenience in description be called an inner side wall panel, is hinged to the rear wall panel 2 along a score line 7 extending substantially parallel to score lines 4 and 5. A somewhat similar but slightly larger outer side wall panel 8 is hinged to the front wall panel 3 along score line 9 which extends substantially parallel to the score lines 4, 5 and 7. A securing flap 10 is hinged to the inner side wall panel 6 along the score line 11 extending substantially parallel to the score line 7. An opposite securing flap 12 is hinged at the opposite end of the blank to the outer side wall panel 8 along the score line 13 extending substantially parallel to score line 9. It will be noted that score lines 4, 5, 7, 11, 9 and 13 are substantially parallel and extend transversely across the blank.

The ends of the container are formed by pairs of inturning end wall supporting and end wall sealing flaps which are hingedly connected to the front, rear, side walls of the container. A pair of end wall supporting flaps 14 and 14' are connected to the side wall panel 1 by parallel score lines 15 and 15'. Substantially similar end wall supporting flaps 16 and 16' are connected to the inner side wall panel 6 along parallel score lines 17 and 17' and another pair of inturning flaps 18 and 18' are connected to the outer side wall panel 8 along parallel score lines 19 and 19' respectively. It will be noted that the supporting flaps 14 and 16 and 14' and 16' are of substantially the same dimensions, while inturning flaps 18 and 18' are somewhat shorter. A pair of side wall sealing panels 20 and 20' are connected to the rear wall panel 2 along a pair of parallel score lines 21 and 21', while a similar pair of side wall sealing panels 22 and 22' are connected to the front wall panel 3 along a pair of parallel score lines 23 and 23' respectively. Suitable minor variations in the dimensions and alignments of the various related panels and scores of the blank A as shown in Fig. 1 may be necessary or desirable to facilitate square and uncrowded folding assembly thereof into container form, especially when the sheet material employed is of relatively heavy gauge.

The outer side wall panel 8 of the container is provided with a dispensing opening 25 while the inner top wall panel 6 may be provided with an encircling line of perforations 27 defining an inner disc 26 which can be torn out to provide an opening 26' which aligns with opening 25 when the container is fully assembled (see Fig. 16). The outer side wall panel 8 is also provided with a U-shaped slit forming a tab or tongue 30 defined by a cut 28 and a curved cut 29 extending from the cut 28 at right angles thereto and terminating at the score line 19. The tab or tongue 30 thus is free to hinge about the score line 19. The cuts 28 and 29 provide an opening through which a portion of the dispensing slide may extend, as will hereinafter be brought out.

A suitable form of blank for the closure member is shown in Fig. 2. It comprises a rectangular main or body portion 31 of a width substantially equal to the width of the carton side panel and a length substantially equal to one-half the length of the carton side panel. A narrower rectangular stem or tab portion 32 is integral with the body portion 31. The body portion has adjacent edges 31' adapted to be guided between

the side walls of the carton. The stem or tab portion 32 has side edges 32' adapted to be guided between the edges of the U-slit in the carton. Forward shoulder edges 31'' extend to either side 5 from the stem or tab portion and provide abutment edges preventing a complete withdrawal of the closure member through the U-shaped slit in the carton. A score line 35 may be provided to facilitate grasping of the end 34 of the stem or tab portion.

The container forming blank A, as shown in Fig. 1, may be assembled into collapsed shell form on an automatic strip gluing and folding machine of standard design. This machine operates to 15 apply a strip of adhesive to the outside face of the inner securing flap 10 and thereupon folds the inner side wall panel 6 about score line 7 so as to overlie the inside face of the rear wall panel 2, as illustrated more particularly in Fig. 3. Next, 20 the machine folds front wall panel 3 about score line 5 so as to overlie the inside face of the side wall panel 1, the top-end of front wall panel 3 being pressed into firm adhesive engagement with the securing flap 10. Thus partially assembled 25 the blank appears as shown in Fig. 4. As the next step in the continuous machine operation, a strip of adhesive is applied to the inside face of the outer securing flap 12, whereupon the said flap 12 is folded under to overlie and be pressed into firm 30 adhesive engagement with the outside face of the rear wall panel 2, as indicated in Fig. 5. The blank, flat-folded and glued as shown in Fig. 5, provides a collapsed tubular shell, quantities of 35 which can be packed together in close stacked relationship so as to require a minimum of space and packing material, and, so stacked and packed, may be shipped to the product manufacturer for further assembly, filling and sealing, with minimum risk of damage in handling or otherwise.

40 The product manufacturer assembles the collapsed shells to form containers as needed. The assembly operations carried on by the product manufacturer may be performed on a standard forming, filling and sealing machine. The collapsed shell as shown in Fig. 5, when fed into such a machine, is first expanded into rectangular form as indicated in Fig. 6, the front wall panel 3, rear wall panel 2, side wall panel 1, and the overlapping inner and outer top wall panels 50 6 and 8 being firmly secured together as hereinbefore described to provide a tube of generally rectangular cross-section. The machine then operates to close and seal one of the open ends of the expanded shell by inwardly folding the supporting flaps 14, 16 and 18 so that they extend substantially in alignment. It will here be noted by referring to Figs. 6 and 7 that the flaps 14 and 16 are substantially co-extensive, with their free edges x substantially in abutment. The 55 other inturning flap 18 is shorter than the inturning flap 16 which it overlies, as fully shown in Fig. 7. The machine then operates to turn outward and apply adhesive to the inside faces of the end wall sealing panels 20 and 22, covering substantially the entire inner surfaces thereof. When the end wall sealing panel 20 is folded to overlie the inturned flaps 14, 16 and 18, pressure is applied thereto so that the adhesive g will firmly 60 adhere to and heal the side wall sealing panel 20 to the full surface area of the inturned supporting flap 14, to the full surface area of the short inturned flap 18, and to that surface area of the inturned supporting flap 16 which extends beyond the edge x of the flap 18. As the final 65 operation, the companion end wall sealing panel 70 75

22 is then folded to overlie and be pressed into firm adhesive engagement with the outside face of the previously inturned end wall sealing panel 20, as illustrated in Fig. 8.

It will be noted that the outer side wall panel 8 has not been adhesively secured to the inner side wall panel 6, in order to permit a closure member to be inserted between these panels and slide snugly therebetween. It is therefore obvious that if the powdered or granular contents were permitted to leak between the inner and outer top wall panels 6 and 8 respectively, this material will eventually escape through the discharge opening 25 in the top wall panel even though the closure member is in its closed position. However, such leakage is effectively prevented by the novel arrangement of inturned flaps 14, 16 and 18, all of which are firmly secured across their full width by adhesive g to the inner end wall sealing panel 20. Leakage of the contents to the exterior of the container is further and finally prevented when the outer end wall sealing panel 22 is firmly adhesively secured to the inner end wall sealing panel 20.

With one of its ends thus closed and sealed, the partially assembled container is inverted, as shown in Fig. 9, and filled with contents through the open end thereof. This end may then be closed and sealed on the same machine or one very similar to that which closed and sealed the other end. Prior to such closing and sealing, however, the closure member B, as shown in Fig. 2, is inserted between the inner side wall panel 6 and the outer side wall panel 8, by spreading apart the respective inturning flaps 16' and 18', as shown in Fig. 9. The tab portion 34 of the closure member is threaded through the U-shaped slit 28-29 in the outer wall panel 8, which is opened by depressing the tab or tongue 30, permitting the tab portion 34 to overlie the tab or tongue 30, as shown in Figs. 10, 11 and 12. When thus arranged the body section 31 of the closure member will fully cover the dispensing opening 25 in the outer wall panel 8, as shown in Figs. 10, 11 and 12.

The sealing machine operates to fold the flaps 14' and 16' inwardly so as to extend substantially in alignment and the secondary flap 18' so as to overlie the flap 16'. Adhesive is applied to the inside faces of the end wall sealing panels 20' and 22' whereupon end wall sealing panel 20' is folded inwardly and pressed into firm adhesive engagement with the exposed faces of the inturned flaps 14', 16' and 18'. By following this method of sealing there is no opportunity for the contents to sift between the supporting flap 16' and the inturned flap 18' and to escape between the inner top wall panel 6 and the outer top wall panel 8. This effective seal results from the fact that the exposed end portion 16'' of the supporting flap 16' is adhesively secured through its full width to the overlying side wall sealing panel 20', as shown in Fig. 14. As the final sealing operation, side wall sealing panel 22' is folded over and pressed into firm adhesive engagement with the outside face of the previously inturned side wall sealing panel 20'. Thus assembled the carton appears in cross-section in Figs. 14 and 15.

When access to the contents is desired, the end 34 of the tab portion 32 is grasped and pulled outwardly, exposing the inner side wall panel 6 through the aperture 25 in the outer top wall panel 8. The disc 26' defined by the line of perforation 27 in the inner top wall panel 6, may then readily be punched out by the consumer, permitting pouring or removal of the contents

through the opening thus formed. It will be further noted that the abutment edges 31'' of the closure member limits the extent of its withdrawal and when the closure member has been drawn out to its full extent it will be noted that the edges 31'' will abut against the ends of the U-slit terminating at the hinged end of the inturned flap 18'. It will be further noted that the side edges 31' of the body portion are substantially in abutting yet sliding contact with the inside face of the wall panel 3 and the outer securing flap 12, so that the closure member moves in a substantially straight line when sliding.

Fig. 17 illustrates a prepared blank A' of suitable material from which a dispensing container of somewhat modified construction may be formed. The blank A' comprises enclosing vertical wall panels 41, 42, 43, 44 and 45 hingedly connected along their side edges at score lines 49, 50, 51 and 52, respectively. When the container is assembled, panel 45 at one end of the blank forms an inner vertical wall panel and panel 41 at the other end of the blank forms an outer vertical wall panel which completely overlies the inner panel 45. An inner securing flap 46 is hingedly connected to a side edge of the inner panel 45 along score line 53, while at the other end of the blank an outer securing flap 47 is hingedly connected along score line 48 to the outer panel 41. It will be noted that score lines 48, 49, 50, 51, 52 and 53 are substantially parallel and extend transversely across the blank.

A pair of end closure or sealing flaps 60 and 62 extend from the top ends of panels 42 and 44 and are hingedly connected thereto along score lines 61 and 63 respectively. A similar pair of end closure or sealing flaps 60' and 62' extend from the bottom ends of panels 42 and 44 and are hingedly connected thereto along score lines 61' and 63' respectively. A pair of closure supporting flaps 54 and 56 extend from the top ends of panels 43 and 45 and are hinged thereto along score lines 55 and 57 respectively. Another pair of closure supporting flaps 54' and 56' extend from the bottom ends of panels 43 and 45 and are hinged thereto along score lines 55' and 57'. A supplemental inturning flap 58 extends from the tab end of the outer side wall panel 41 and is hinged thereto along score lines 59, and a similar supplemental inturning flap 58' extends from the bottom end of panel 41 and is hinged thereto along score line 59'. Suitable minor variations in the dimensions and alignments of the various related panels and scores of the blank A', as shown in Fig. 17, may be necessary or desirable to facilitate square and uncrowded folding assembly thereof into container form, especially when the sheet material employed is of relatively heavy gauge.

The prepared blank A', as shown in Fig. 17, may be assembled in collapsed shell form in the same manner that the blank shown in Fig. 1 is assembled. This operation can be performed in a standard box folding and gluing machine which first operates to apply adhesive in strip form to the outside face of inner securing flap 46, folds the inner vertical wall panel 45 about score line 52 so as to overlie wall panel 44 and folds panel 42 about score line 50 so as to overlie panel 43 whereby that portion of enclosing panel 42 which is adjacent to score line 49 will become adhesively secured to the underlying inner securing flap 46. During further continued travel of the blank through the strip folding and gluing machine, outer securing flap 47 which overhangs the main

body of the blank is then coated with adhesive and is folded into adhesive engagement with the enclosing panel 44 adjacent to score line 52. As thus assembled, a collapsed tubular shell is presented which permits stacking, shipping and storage of large numbers of such collapsed shells in a limited space.

The product manufacturer, on receiving the collapsed shells, then proceeds either manually or mechanically, to expand them into tubular form and to close and seal one of the open ends thereof. If mechanically, this operation can be performed on readily available standard machine which, after automatically expanding each shell, operates next to turn inwardly the closure supporting flaps 54' and 56' so that they extend substantially in alignment and substantially simultaneously folds in the shorter inturning flap 58' so as to overlie the supporting flap 56'. The flaps 54' and 56' preferably are of such length that, when thus inturned, they will meet in substantially edge-to-edge abutment. The machine operates to apply adhesive to the inside faces of the closure flaps 60' and 62', folds closure flap 60' into firm adhesive engagement with the substituting flap 54', and with the inturning closing flap 56'. The container thus far assembled appears in Fig. 19, in which condition it is ready to receive contents.

It will be noted that outer vertical panel 41 is provided with a dispensing opening 66 and a tab or tongue 63 defined by a U-shaped slit comprising a cut 64 and a pair of spaced cuts 65. A closure member B' substantially in the shape of a T and formed from a single piece of suitable material, as more fully shown in Fig. 18, is provided which comprises a body section or covering portion 71 having laterally extending wing sections 72, providing shoulder portions 73 and forming head of the T. A finger grip portion 74 forming the leg of the T is hinged to the cover portion 71 along a transversely extending score line 75 and can be grasped when assembled with a container for the purpose of moving the closure member.

As shown in Fig. 19, the closure member B' is inserted between the outer panel 41 and the inner panel 45 by spreading apart the primary inturning flap 56 and the secondary inturning flap 58. The finger grip portion 74 is threaded through the U-slit or opening formed by depressing the tab or tongue 63 in the outer panel 41. When in normal assembled position the closure member covers the inner panel 45 so that it is not visible through the opening 66. When the closure member is drawn into dispensing position, as shown in Fig. 20, the inner panel 45 is clearly visible through the opening 66 and when the disc 67 circumscribed by the perforated line 68 in the inner panel 45 is punched out, a dispensing opening 61' as shown in Fig. 17 is provided for dispensing of the contents.

When the product manufacturer has properly inserted the closure member B' in operative position and filled the partially assembled container, with contents, as shown in Fig. 19, the last remaining end of the container may be closed by infolding the flaps 56 and 54 so as to extend substantially in alignment, and substantially simultaneously infolding the secondary flap 58 so as to overlie the primary flap 56, leaving the end portion of flap 56 exposed. As the next step, adhesive is applied to the inside face of the closure flaps 60 and 62, closure flap 62 is folded and pressed into adhesive engagement with the inturned flaps 54, 56 and 58, and finally closure

flap 60 is folded and pressed in adhesive engagement with the outside face of closure flap 62, providing a completed dispensing carton as shown in Fig. 20. The consumer can readily obtain access to the contents by drawing the closure member B' to the position shown in Fig. 20 and punching out the disc 67 in the inner panel 45. It will be noted that the shoulder portion 73 of the closure member will abut against the material surrounding the ends 65' of the U-slit 65, limiting further withdrawal of the closure member. The aligned dispensing openings 66 and 67 may readily be closed off by grasping the finger grip portion 74 and sliding the closure member back into closed position so that the covering portion 71 thereof closes off the aligned openings 66 and 67.

The dispensing carton above described and illustrated in Figs. 13 and 20, is substantially sift-proof and is especially adapted for granular or powdered material. An effective seal which prevents the escape of the contents between the inner and outer panels which carry the dispensing openings, is effectively provided by the primary and secondary inturning flaps hinged to the respective ends of the inner and outer panels which are glue-sealed to the overlying closure flap to prevent the escape of the contents between the primary and secondary inturned flaps.

In cases where a package for pills, pellets or tablet-shaped products is desired, it will be appreciated that the container need not be made sift-proof. There is shown in Fig. 21 a prepared blank A' from which a dispensing container for such packaging uses may be formed. The blank 35 as shown in Fig. 21 comprises enclosing panels 82, 83, 84, 85 and 86, which are hinged connected at their side edges along the respective score lines 89, 90, 91 and 92, providing in effect a blank having five panels to form a four-sided enclosure. A securing flap 87 is hinged connected along score line 93 to end panel 86, which for convenience may be designated the inner top panel. A further securing flap 81 is hinged connected to the panel 82 along the score line 88. The score lines 88, 89, 90, 91 and 93 extend across the blank and substantially parallel so as to provide a container having substantially rectangularly shaped enclosing walls. A pair of closure panels 94, 94' are hinged connected to the opposite ends of panel 82, which may also be referred to as the outer top panel, along parallel extending score lines 95 and 95'. A pair of tuck-in flaps 96 and 96' hinged to the opposite closure panels 94, 94' along parallel score lines 97 and 97', are tucked into the container when assembled to retain the closure panels 94 and 94' in closed position. A pair of closure supporting flaps extend from the end of the side panel 85 along score lines 99 and 99'. A similar pair of closure flaps 100 and 100' are hinged along parallel score lines 101 and 101' to the opposite ends of panel 83.

When a container is assembled from the blank A' shown in Fig. 21, the inner top panels 86 will underlie the outer top panel 82 to provide inner and outer panels, while the securing flap 87 will underlie the side wall panel 83. The dispensing slide B'', formed from the blank as shown in Fig. 22, will be received between the inner top panel 86 and the outer top panel 82. A dispensing opening 102 is provided in the outer top panel 82. The inner top panel 86 is provided with a line of perforations 103 which define a punch-out disc 104, which when punched out provides a dispensing opening 103' in registry with opening 102. The 75 outer top panel 82 is also provided with a U-slit

106 whose ends terminate at the score line 95' to define a tongue 105.

The closure member B'' having substantially the form of a T may also be formed from a single blank of suitable material comprising a body section or covering portion 110 provided with wing sections 111 having abutment shoulders 112. A finger grip portion 113 extends from the covering portion 110.

The container forming bank A'' may be assembled by the box maker into collapsed shell form on a strip gluing and folding machine at a high production rate. As shown in Fig. 23, a strip of adhesive g is applied to the outside face of the securing flap 81, whereupon the panel 86 is folded about score line 92 so as to overlie the panels 84 and 85. The panels 83 and 82 are then folded about score line 90 so as to overlie and adhesively engage the securing flap 81, as illustrated in Fig. 24. Adhesive is then applied to the inside face of the securing flap 81 which overhangs the remaining parts of the blank, as shown in Fig. 24, whereupon the flap 81 is folded about score line 88 and pressed into adhesive engagement with the outside face of the panel 85, forming a collapsed but assembled shell as shown in Fig. 25. The collapsed shell as shown in Fig. 25 may be stacked, stored and shipped in a minimum space and held in stock by the product manufacturer until needed.

The product manufacturer can quickly assemble the collapsed shell as shown in Fig. 25 without the aid of any equipment. In assembling the collapsed shell into container form, the body of the blank is expanded into the form of an open tube, as shown in Fig. 26. Closure supporting flaps 98' and 100' are then turned inwardly as shown in Fig. 26, closure panel 94' folded thereover, and tuck-in flap 96' inserted into the expanded shell, as shown in Fig. 27. The closure member may then be inserted between the inner panel 86 and the outer panel 82, as shown in Fig. 28, and the finger grip portion 113 thereof threaded through the U-slit formed in the outer panel 82 by pressing down arcuate tongue 105, so that the finger grip portion 113 overlies the tongue 105. The container may then be filled with the product, the closure supporting flaps 98 and 100 be turned inwardly, closure panel 94 folded thereover, and tuck-in flap 96 inserted into the container so as to lie adjacent the inside face of the third enclosing panel 84.

The consumer may readily obtain access to the contents by exerting thumb pressure on the finger grip portion 113 and drawing the closure member outwardly as shown in Fig. 29. The closure can be readily moved since it lies flat between the adjacent smooth surface of the inner panel 86 and the outer panel 82 and is guided by the folded side edges of the latter. When the closure member has been drawn to the position shown in Fig. 29, the disc 103 may be punched out of the inner panel 86 by consumer to provide a dispensing opening 103' in the inner panel, which aligns with the dispensing opening 102 in the outer panel, as shown in Fig. 30. Reclosure of the carton may be effected by moving the closure member in the opposite direction. It will be noted that the closure member can only be moved a sufficient extent to expose the line of openings and when drawn to its full open position, the shoulder portion 112 thereof will abut ends of the U-slit.

It is obvious that in all the forms of containers hereinbefore described the closure member

may be assembled with the container body while the tubular container blank is still in its collapsed form. The assembly may therefore take place at the plant of the container manufacturer before shipment to the merchandise manufacturer of the collapsed blank. In this case the blank requires merely expansion and sealing but no assembly of loose parts at the merchandise manufacturer's plant.

It is now seen that an efficient attractive dispensing container is provided, the various forms of which are wholly formed from paperboard or similar material, and is adapted for the packaging of products which have heretofore been packaged to a large extent in cans or boxes, partially or wholly from sheet metal. In one form of the invention the container is so constructed as to prevent sifting of the contents between the paperboard layers formed in the container and thus prevent escape or loss of the contents. The closure member may be formed from a flat blank of paperboard, which requires no folding or gluing, and its flat side surfaces slide smoothly between the inner and outer panels of the container. Containers made in accordance with this invention can be manufactured and filled on standard box assembly machines at a high production rate with the use of substantially no skilled labor, and can be shipped to and stored by the product manufacturer as collapsed shells effecting economics in shipping and storage space, and thereafter can be quickly assembled by the product manufacturer.

A particular feature of the forms of containers hereinbefore described is that the container may repeatedly be opened and reclosed by the consumer without the use of any tool and without defacing the container.

While certain novel features of the invention have been disclosed and are pointed out in the annexed claims, it will be understood that various omissions, substitutions and changes may be made by those skilled in the art without departing from the spirit of the invention.

What is claimed is:

1. A box or carton comprising a multi-sided tubular body formed of side walls, and foldable flaps for closing its ends, one side wall consisting of an inner panel and an outer panel, said inner panel having a securing tab hinged thereon secured to the inner surface of the wall panel adjacent said outer panel, said outer panel having a securing tab hinged thereon secured to the outer surface of the wall panel adjacent said inner panel, said inner and outer panels lying unattached face to face, each panel having a dispensing aperture therein, the apertures being in registry, the outer panel having further a U-shaped slit therein; and a substantially T-shaped closure member inserted between said outer and inner panels with freedom to slide therebetween, said closure member having a finger operable portion extending through said slit, the ends of the slit extending to an edge of said outer panel, a side flap hinged to said outer panel along said edge, said side flap abutting an edge of said closure member in withdrawn position and forming a stop limiting the longitudinal movement of said closure member.

2. A box or carton comprising a multi-sided tubular body formed of side walls, and foldable flaps for closing its ends, one side wall consisting of an inner panel and an outer panel, said inner panel having a securing tab hinged thereon secured to the inner surface of the wall panel

adjacent said outer panel, said outer panel having a securing tab hinged thereon secured to the outer surface of the wall panel adjacent said inner panel, said inner and outer panels lying unattached face to face, each panel having a dispensing aperture therein, the apertures being in registry, the outer panel having further a slit therein in the shape of a U closed towards said dispensing aperture, the legs of the U being substantially parallel; and a substantially T-shaped closure member inserted between said outer and inner panels with freedom to slide therebetween, said closure member having a main body portion of a width substantially equal to the width of said inner panel, said body portion representing the head of the T, and a finger operable portion of a width substantially equal to the width of said U, said finger operable portion extending through said slit and representing the leg of the T, the ends of the slit extending to an edge of said outer panel, a side flap hinged to said outer panel along said edge, said side flap abutting an edge of said closure member in withdrawn position and forming a stop limiting the longitudinal movement of said closure member.

3. A box or carton comprising a multi-sided tubular body formed of side walls, and foldable flaps for closing its ends, one side wall consisting of an inner panel and an outer panel, said inner panel having a securing tab hinged thereon secured to the inner surface of the wall panel adjacent said outer panel, said outer panel having a securing tab hinged thereon secured to the outer surface of the wall panel adjacent said inner panel, said inner and outer panels lying unattached face to face, each panel having a dispensing aperture therein, the apertures being in registry, the outer panel having further a slit therein in the shape of a U closed towards said dispensing aperture, the legs of the U being substantially parallel and terminating at a fold line defined edge of the outer panel; and a substantially T-shaped closure member inserted between said outer and inner panels with freedom to slide therebetween, said closure member having a main body portion of a width substantially equal to the width of said inner panel, said body portion representing the head of the T, and a finger operable portion of a width substantially equal to the width of said U, said finger operable portion extending through said slit and representing the leg of the T, the ends of the slit and said fold line extending to an edge of said outer panel, a side flap hinged to said outer panel along said edge, said side flap abutting an edge of said closure member in withdrawn position and forming a stop limiting the longitudinal movement of said closure member.

4. A box or carton made from a single blank of board comprising five side wall panels forming a tubular body having four side walls, one side wall being of double thickness and consisting of an inner and an outer panel in overlying relationship, opposite surfaces of said inner and outer panels being unattached, each panel having a dispensing aperture therein, the apertures being in registry, the outer panel having a slit therein; a slide member inserted between said inner and outer panels for sliding movement therebetween, said slide member having a finger operable tongue extending through said slit whereby said slide member may be moved to open and close said apertures; a pair of end flaps hinged to opposite ends of said inner and of said outer panel; a pair of

end flaps hinged to the ends of the side wall panel opposite said double side wall, said end flaps being foldable into carton end forming position; and end panels hinged to the ends of two of the remaining side walls, said end wall panels being adapted to be folded into carton end closing position over said end flaps.

5. A box or carton comprising a four sided tubular body formed of side walls, one side wall being of double thickness and consisting of an inner panel and an outer panel in overlying relationship, said inner panel having a hinged securing tab thereon secured to the inner surface of the wall panel adjacent said outer panel, said outer panel having a hinged securing tab thereon secured to the outer surface of the wall panel adjacent said inner panel, said inner and outer panels lying unattached face to face, each panel having a dispensing aperture therein, the apertures being in registry, the outer panel having a slit therein; a slide member inserted between said inner and outer panels for sliding movement therebetween, said slide member having a finger operable tongue extending through said slit whereby said slide member may be moved to open and close said apertures; a pair of end flaps hinged to opposite ends of said inner and of said outer panel, the end flaps on said outer panel being shorter than the end flaps on said inner panel; a pair of end flaps hinged to the ends of the side wall panel opposite said double side wall, said end flaps being foldable into carton end forming position; and end panels hinged to the ends of the two remaining side walls, said endwall panels being adapted to be folded into carton end closing position and to be adhesively secured to each other and the three underlying end flaps at each carton end.

6. A blank formed from a single piece of foldable sheet material for forming a four sided dispensing carton having a dispensing aperture in one side wall, the blank comprising five side wall forming panels hinged to the first and last panel having dispensing apertures therein adapted to register when the blank is folded, one of said first and last wall panels having further a slit therein in the shape of a U closed towards said aperture, the slit being adapted to accommodate the end of a dispensing slide, a securing tab hinged to the first and last wall panels along a fold line parallel to said side fold lines, end flaps hinged to the first, third and last wall panels along end fold lines, and end panels hinged to the remaining two wall panels along end fold lines.

7. A blank formed from a single piece of foldable sheet material for forming a four sided dispensing carton having a dispensing aperture in one side wall, the blank comprising five side wall forming panels hinged to the first and last wall panels of the blank having dispensing apertures therein adapted to register when the blank is folded, one of the first and last wall panels having further a slit therein in the shape of a U closed towards said aperture, the legs of the U being substantially parallel and terminating at a fold line bordering said last named wall panel, a securing tab hinged to the first and last wall panels, end flaps hinged to the first, third and last wall panels along end fold lines, the end flaps connected to the wall

17

panel having the slit therein being shorter than the remaining end flaps, and end panels hingedly connected to the remaining two wall panels along end fold lines.

MARSHALL I. WILLIAMSON.
